UNITED STATES PATENT OFFICE

ALBERTINE BUELLAND, OF NEW YORK, N. Y.

COMBINED BOOK HOLDER AND MARKER

Application filed March 21, 1929. Serial No. 348,778.

My invention relates to a device for holding and supporting books, newspapers and similar articles in which laterally extending means, permanently connected with the device, are provided for engaging and holding flat the pages of the article when in use or on display as in a shop window. These means are freely releasable so as to easily disengage and engage the pages as they are turned. In particular, the invention relates to a device provided with angularly adjustable supporting means permitting it to be used as a page marker when the article, for example a book, is in use.

One of the objects of my invention is to provide a device of firm but light construction which may be used for holding and supporting articles and for holding the pages flat when the article is in use or on display in a shop window, and which is provided with angularly adjustable supporting means permitting the device to be used as a page marker when the article is not in use.

Another object is to provide a combined book holder and page marker with vertically and separately adjustable means so as to enable it to be used with books and other articles of various lengths.

Another object is to provide a combined book holder and page marker which is constructed of a minimum number of parts and which may be economically manufactured and rapidly and easily assembled.

With the above and other objects in view, my invention consists in the parts, improvements and combinations more fully pointed out hereinafter.

Referring now to the drawing:

Figure 1 is a front elevation of one embodiment of the invention, the book, shown in dotted lines, being illustrated held and supported with its pages flat.

Figure 2 is a side elevation of the form shown in Figure 1,

Figure 3 is a longitudinal cross-sectional view of the form shown in Figure 1.

Figure 4 is a front elevation of another embodiment of the invention, showing the holding member provided with a pair of separated legs, and,

Figure 5 is a detail view of my preferred form of page holder and marker spring.

The device of my invention provides an improved and simplified form of book holder and page marker. It is provided with means for holding and supporting books or other articles of various lengths and includes releasable means permanently connected to the device for engaging the top edge or margin of the pages when the article, for example a book, is in use so as to hold the pages flat. The book may thus be held and supported open with its pages held flat and so displayed in shop windows, or may be read without interference with the printed matter of the pages, the releasable page holding means permitting the pages to be easily turned on release of the marker. By means of an angularly adjustable supporting member, the device may be used as a page marker when the article is not in use.

In the forms of the invention illustrated, Figures 1 to 3, inclusive show the device to comprise a holding member 1, having a vertically extending portion 2, and a horizontal extension 3, the latter being adapted to engage the bottom of the article to be held. In Figure 4, the holding member 1, is shown provided with a pair of separated legs 4, 5, each having a horizontal extension 6.

Means are provided for supporting the article when in use or on display, the said means being angularly adjustable so as to permit the device to be easily carried about and so used as a book page marker.

As illustrated the holding member 1, is provided at its upper rear face with a strap 7. In the preferred form this strap is provided by punching out the metal of the holding member, leaving a cut-out portion in the holding member 1, and providing a rearwardly projecting strap. A supporting member 8 is provided, having a pair of supporting legs 9, 10 in fixed relation to each other, and having its upper end, terminating in a bent portion 11, which is passed through the strap 7 of the holding member 1. The strap secures the member 8 to the holding member and the cut-out portion in the holding member allows the bent portion 11 to 100

slide about the strap, so that it may be swung from or against the holding member.

Means, including a vertically adjustable member, are provided enabling the device to be used with books or other articles of various lengths.

In the form of the invention illustrated, I provide a narrow strip 12 which is secured to the holding member and is adapted to be separately moved vertically with relation thereto. I prefer to secure the vertically adjustable member to the holding member by means of a pair of straps 13, 14, which are stamped out of the face of the holding member. Straps 13, 14, frictionally engage the strip 12, so that the strip may be moved to and held in various positions.

Means are provided permanently connected to the device for holding the pages of the article open and flat while the article is in use or display, the said means being readily releasable so as to permit the pages of the article to be turned.

In the preferred form of the invention, these means include a spring member 15 permanently connected to the vertically adjustable member. The spring 15, is provided with a lip 16, which is adapted to engage the top edge or margin of the book or article. The spring is extended laterally so that it will grip both pages of the book when the book is open, at the top margin thereof.

By these means the book or other article may be firmly held and supported with its pages open and flat, and thus used for display purposes or reading, the spring gripping the top edge or margin of the book so as not to interfere with the printed matter. Spring member 15, as shown is readily releasable, as by ears 17, projecting from the spring. If the book is held for reading purposes, the spring may be easily released by pressing the ears 17, and the page turned. Upon release of the ears by the user, the spring will return to place and hold the pages flat again.

By means of the adjustable supporting member and the firm but light construction of the device, it may be used as a page marker when the article with which it is used is not in use.

If the device is used with a book and the reader has finished, the device may be shifted to engage the side, instead of the back of the book. The spring 15 may be left in place in the book, to indicate the page at which to resume, and the supporting member 8, may be swung flat against the back of the holding member 1. The device may thus be carried about with the book from place to place and as desired set up to hold the book with its pages flat at the place where the reader had previously left off.

Having thus described the invention and its operation, it will be understood that changes may be made in carrying the inven-

tion into effect, without departing from the principle of the invention.

What I claim is:

1. A combined holder and page marker for books or the like comprising a holding member adapted to engage the back or to be shifted and engage the cover of a book, an angularly adjustable supporting member, a strap for loosely connecting the supporting member to the holding member, a vertically and separately adjustable member, straps for securing the vertically adjustable member to the front face of the holding member, and spring means for releasably engaging the upper blank edge of adjacent open pages of a book or the like.

2. A combined holder and page marker for books or the like comprising a holding member adapted to engage the back or to be shifted and engage the cover of a book, an angularly adjustable supporting member, said holding member being provided with a cut-out portion forming a strap projecting from the rear face thereof, the upper end of the supporting member being bent and passed thru said strap, a vertically and separately adjustable member carried by the holding member, and spring means carried by said vertically adjustable member for engaging and marking the pages of a book, said means being adapted to engage the upper blank edge of adjacent open pages of a book or the like.

3. A combined holder and page marker for books or the like comprising a holding member adapted to engage the back or to be shifted and engage the cover of a book, said member having a pair of fixed, separated legs, each provided with a horizontal extension adapted to engage the bottom of a book or the like, an angularly adjustable supporting member connected to the holding member, said supporting member being provided with a pair of fixed, separated legs, a vertically and separately adjustable member carried by the holding member, and releasable spring means carried by the vertically adjustable member, said means being adapted to engage the upper blank edge of adjacent open pages of a book or the like.

4. A combined holder and page marker for books or the like comprising a holding member adapted to engage the back or to be shifted and engage the cover of a book, said member having a pair of fixed, separated legs, each provided with a horizontal extension adapted to engage the bottom of a book or the like, an angularly adjustable supporting member connected to the holding member, a vertically and separately adjustable member carried by the holding member, and spring means carried by the vertically adjustable member and adapted to engage the upper blank edge of adjacent open pages of a book or the like, and means projecting from

said spring for freely releasing the spring.

5. A combined holder and page marker for books or the like comprising a holding member adapted to engage the back or to be shifted and engage the cover of a book, said member having a pair of fixed, separated legs, each provided with a horizontal extension for engaging the bottom of a book or the like, an angularly adjustable supporting member, a strap projecting from the rear face of the holding member and loosely engaging the upper end of the supporting member, a vertically and separately adjustable member, a pair of straps projecting from the front face of the holding member, the vertically adjustable member being frictionally held by said straps, freely releasable spring means carried by the vertically adjustable member, said means being adapted to engage the upper blank edge of adjacent open pages of a book or the like, and a projecting ear carried by the spring for freely releasing the spring.

In testimony whereof, I have signed my name to this specification.
